UNITED STATES PATENT OFFICE.

FRANK M. POTTER, OF CHICAGO, ILLINOIS.

FIRE ESCAPE.

Application filed January 16, 1924. Serial No. 686,527.

The present improvements relate to fire escapes of the tubular type in which the escaping person slides from a higher level of the building to a place near the ground. 5 Its chief objects are to provide for greater safety and comfort to the individual making his escape, to provide a stronger construction adapted longer to withstand the effect of weather and other destructive influences, to provide a construction in which materials may be employed better suited to the purpose and which may be of relative light-weight stock, and to overcome objectionable atmospheric conditions found in 15 single-tube devices of this general kind.

In the accompanying drawings, which form a part of this specification, Figure 1 represents a building having my improved fire escape applied thereto; Fig. 2 is a 20 greatly enlarged fragmentary sectional view as on the line 2—2 of Fig. 1; Fig. 3 is a cross-sectional view as on the line 3—3 of Fig. 2; Fig. 4 is a medial vertical sectional view of the entrance-passageway-forming 25 means; and Fig. 5 is a greatly enlarged fragmentary sectional view showing the connection of several of the parts.

It is old practice to lead a tubular chute from an upper level of a building to a place 30 near the ground, and the almost invariable practice in such use is to extend the chute slantingly downward for the most part in a straight line alongside the building substantially as shown in Fig. 1. It almost always 35 happens that the chute thus extends past or above the windows of lower stories. It often happens, too, that the chute passes downward between adjacent buildings and past windows thereof or in the vicinity of 40 small wooden houses, sheds, or other structures. Such adjacent buildings may be quite inflammable, as may be also the building on which the structure is mounted. In all 45 such instances the flames of conflagration are very likely to play upon the tubular chute, and it has frequently happened in such instances that the single metal tube heretofore employed has become so hot as seriously to injure persons sliding therethrough.

According to these improvements the inner tube 10, which may be considered of usual and ordinary construction, but which may be of improved construction, is 50 encompassed or surrounded in spaced-apart relation by an outer tubular member 11, and

this outer tube preferably extends from one end of the inner tube to the other so that the lower end of the outer tube will be sure to be carried to a place near the ground 60 where there is little or no likelihood of the presence of flames. It is shown as being held in position by a plurality of stays or supports 12 bolted to both the inner and outer tubular members. I preferably employ four such stays at each of the joints of the cylindrical sections comprising the outer and inner tubes as illustrated.

The outer tubular member 11, which is supported as by brackets 15 to the building, is preferably formed of cylindrical sections having angle iron members 16, Fig. 5, riveted as at 17 to the tubular walls 11 and providing abutting flanges through which bolts 18 extend. Bolts 19 hold the 75 stays 12 to one of these angle iron rings 16. The inner tube 10 may sufficiently strongly be formed by overlapping or telescoping end portions and riveting them together, and bolts 20, Fig. 2, may be used 80 instead of rivets at appropriate places to hold the braces 12.

In Fig. 2 the chute slants downward and the person descends through the chute in the direction of the arrow, and the overlapped portions at 22 are made to telescope 85 so to provide an unobstructed sliding surface for the person.

Referring to Fig. 4 it will be noted that the tubular chute 10 terminates in a housed-in passageway-forming structure consisting of a top wall 25, a bottom wall 26, two side walls 27, and a front conical or flaring wall 28, which passageway structure is secured to a top frame part 30, a bottom frame part 31, and two side frame parts, all rigidly secured together and to the building wall, as by cementing or otherwise holding it in place. There is shown also an additional frame consisting of a top part 33, a bottom part 34, and side parts 35 secured to the other frame parts, and a pair of doors 36 (only one shown) adapted to swing inward into an out-of-the-way position are hingedly mounted one at each side of the entrance 105 opening. This particular entrance-passageway structure is more specifically described and claimed in a copending application filed by me contemporaneously herewith as Serial Number 689,872 on fire escapes.

The rigid tubular outer wall 11, Fig. 4, is preferably made to encompass in spaced

apart relation that portion of the passageway-forming structure as is exposed outside the building, and is therefore provided with a flaring part 38 overlying the front wall 28 of the passageway-forming means, and the open space 39 is to be understood as extending around the wall 28 at the sides as well as at the top. I provide also ventilation openings 40 for the inner wall 28 and 10 41 for the outer wall 38, these openings being formed by pressing out the metal in a manner adapted to shield the openings respectively from the weather. These ventilation features provide for a circulation of 15 air throughout the inner and outer tubes from top to bottom thereof at all times.

One important advantage of the double construction of the chute is in the provision of safety and comfort to the occupants of the 20 inner tube in the protection afforded against the overheating of that tube by the flames of conflagration. A second important advantage is in the fact that according to this construction the inner tube 10 may be of a 25 much more satisfactory material than the galvanized sheet iron ordinarily employed, for instance, sheet zinc may be used, which is not only much smoother than galvanized iron, but, importantly, maintains its smooth 30 and substantially uncorroded condition substantially indefinitely. Zinc sheets could not safely be employed for a single-tube construction because of the low melting point of zinc, nor could it be used because of 35 strength considerations unless the sheet material were unusually and objectionably heavy. Relatively light sheet zinc may be employed for the inner tube 10 and thus a very important object is attained in the provision and preservation of an unusually 40 smooth sliding surface. Still other more suitable sheet stock could be employed. According to the present construction the outer tube 11 may be of galvanized iron, and is so 45 strongly put together as to provide the desired strength and to constitute it a carrier for the inner tube, and the inner tube may therefore be formed of relatively light-weight stock. Furthermore, since the inner 50 and outer tubes are secured rigidly together the structure as a whole is greatly strengthened with the result that the outer tube 11 may also be of materially lighter weight stock than that necessary for a single-tube 55 chute.

Another important feature of the construction is that through the provision of an enclosed air space around the inner tube 10 the inner tube is better preserved against 60 the deposit of moisture therein through precipitation, objectionable for various reasons including the lowering of the speed of a person's descent due to increased frictional contact. The presence of such moisture is further obviated by the ventilation feature pro-

vided for the inner tube, and such ventilation also insures proper air conditions in the inner tube at the time of use. The ventilation of the outer tube provides for the carrying away of heated air therein at the time 70 of conflagration, thus preserving the inner tube against objectionable heat, and it also provides for the carrying away of excessively heated air on hot days, when the sun is beating strongly on the device, thereby maintaining the inner tube at a lower temperature and avoiding the stifling conditions sometimes found in single tube chutes under excessively warm weather conditions. 75

The rigid tubular fire escape which extends slantingly downward and for the most part in a straight line alongside the building has thus far been found to be the most satisfactory and useful of all the various tubular chutes hitherto suggested for the purpose, and the present improvements have for their prime object and effect the rendering of that type and character of escape device still more useful and advantageous in highly important respects. 80

I contemplate as being included in these improvements such modifications and departures from what is herein specifically illustrated and described as fall within the scope of the appended claims. 85

I claim:

1. In a fire escape, a rigid tubular chute member open at the bottom and having a materially large part thereof extending in a straight line slantingly downward along the outside of a building, the chute member terminating at a place near the ground horizontally distant from the top of the chute member, and a second rigid tubular structure encompassing the straight portion of the chute member in spaced relation to provide an air space between them. 100

2. In a fire escape, a rigid tubular chute member open at the bottom and having a materially large part thereof extending in a straight line slantingly downward along the outside of a building, the chute member terminating at a place near the ground horizontally distant from the top of the chute member, and a second rigid tubular structure encompassing the straight portion of the chute member in spaced relation to provide an air space between them, the encompassing structure being open to the outer air at the lower portion and also at the upper portion 105 thereof to provide a circulation of air therein. 110

3. In a fire escape, a rigid tubular chute member open at the bottom and having a materially large part thereof extending in a straight line slantingly downward along the outside of a building, the chute member terminating at a place near the ground horizontally distant from the top of the chute member, and a second rigid tubular structure encompassing the chute 115 120 125 130

member in spaced relation substantially from end to end thereof to provide an air space between them, means forming a housed-in passageway leading from the building into the upper end of the chute member, said encompassing structure encompassing also, and in spaced relation, that portion of said passageway-forming structure which is outside the building, the entire compassing structure being open to the outer air at various places to provide a circulation of air therein, the chute member having openings near the top thereof to provide circulation of air in the chute member.

4. In a fire escape of the character described extending slantingly downward to a horizontally distant place near the ground, the combination of two rigid tubular structures one within the other and secured in spaced-apart relation to provide an air space between them, means providing a housed-in entrance passageway leading from the interior of the building to the interior of the inner tubular structure at the upper portion thereof, door means normally closing the entrance passageway where the passageway leads from the building, the inner tubular structure having ventilation means near the top thereof outside the building to provide a circulation of air from the bottom substantially to the top thereof.

FRANK M. POTTER.
